LEONARD ROSE, OF NEW ORLEANS, LOUISIANA.

NON-REFILLABLE BOTTLE.

1,115,976.

Specification of Letters Patent.

Patented Nov. 3, 1914.

Application filed February 12, 1914. Serial No. 818,390.

To all whom it may concern:

Be it known that I, LEONARD ROSE, a subject of the King of Great Britain, residing at New Orleans, in the parish of Orleans and State of Louisiana, have invented a new and useful Non-Refillable Bottle, of which the following is a specification.

This invention relates to improvements in non-refillable bottles.

10 The object of the present invention is to improve the construction of non-refillable bottles and to provide a simple, inexpensive, and practical device, adapted to be readily applied to bottles or analogous receptacles 15 and capable of effectually preventing a bottle from being refilled, whereby the liability of fraudulent refilling with an imitation liquid is eliminated.

With these and other objects in view the 20 invention consists in the construction and novel combination of parts hereinafter fully described, illustrated in the accompanying drawing, and pointed out in the claims hereto appended, it being understood that 25 various changes in the form, proportion, size and minor details of construction, within the scope of the claims, may be resorted to without departing from the spirit or sacrificing any of the advantages of the invention.

30 In the drawing: Figure 1 is a vertical sectional view of a portion of a non-refillable bottle constructed in accordance with this invention. Fig. 2 is a detail perspective 35 view of the valve casing. Fig. 3 is a detail view of the resilient locking ring.

Like numerals of reference designate corresponding parts in all the figures of the drawing.

40 In the accompanying drawing, in which is illustrated the preferred embodiment of the invention, 1 designates a bottle provided with a neck 2 having the walls of its lower portion 3 tapered upwardly in thickness to 45 provide a downwardly tapered opening or passage to form a seat for a packing sleeve 4 which is interposed between the neck, and a valve casing 5 which is tapered to correspond with the taper of the bottle. The 50 valve casing is provided with walls of uniform thickness and it has a downwardly tapered valve chamber 6 for the reception of an inverted conical valve 7. The inverted conical valve, which is of a thickness 55 to prevent it from getting crosswise within the valve casing, is adapted to seat itself

against the inclined walls of the valve casing, and an efficient seating of the valve is thereby effected. Also the valve 7, when closed, depends from the valve casing and 60 extends a considerable distance into the body portion of the bottle, and it is necessary to invert or turn the bottle below a horizontal position in order to unseat the valve. This construction will thereby prevent any liquid from being interposed into 65 the bottle when the latter is in an upright position, and any attempt to force a liquid into the bottle when the latter is in an inverted position will operate to seat the valve 70 and close the neck of the bottle.

The tapered packing sleeve, which is preferably constructed of cork, provides a liquid-tight fit for the valve casing and is adapted to prevent any liquid from leaking 75 out of the bottle or into the same around the exterior of the valve casing, and the bottle is further protected by a horizontal packing ring 8 constructed of cork or other suitable material and provided with an opening 80 corresponding in diameter to the diameter of the upper end of the valve chamber and overlapping the upper edges of the walls of the valve casing and the packing sleeve and having a width equal to the combined thickness 85 of the said parts. The packing ring is adapted to prevent any liquid introduced into the neck of the bottle from leaking between the valve casing and an upper guard 9, and it also serves to confine the valve 90 retaining bar 10 in recesses 11 in the upper edges of the valve casing. The valve casing and the valve, which may be constructed of any suitable material, are preferably made of glass, porcelain, or the like, and the bar, 95 which may also be constructed of any suitable material, is arranged horizontally when the bottle is in an upright position, and its terminal portions fill the recesses 11. The bar limits the outward movement of the valve 100 and confines the same within the valve casing. While it is preferable to secure the valve retaining bar within the recesses of the valve casing by a cork packing ring, other means, of course, may be employed 105 for the purpose. The upper portion of the neck of the bottle is preferably cylindrical, as shown, and the guard 9, which is cylindrical to fit the same, is provided at opposite sides with downwardly and inwardly 110 inclined projecting portions or flanges 12, disposed in spaced overlapping relation

and forming a tortuous passage, which, while permitting a free flow of the liquid contents of the bottle, will prevent a wire or other instrument introduced into the neck 5 of the bottle from interfering with the operation of the valve. The guard, which fits against the upper face of the packing ring, retains the same in its engaging position, and is located within the neck of the bottle 10 by a split resilient locking ring 13, adapted to lie within an annular groove 14 in the exterior of the cylindrical guard 9 while the latter is being introduced into the neck of the bottle, and capable of automatically expanding and engaging an interior annular groove 15 in the neck of the bottle when the groove 14 of the guard is brought into alignment or register with the said groove 15. The split resilient locking ring is constructed 20 of material of a width greater than the depth of the groove 15 of the neck of the bottle, so that when the locking ring is in engagement with the said groove 15, it will also engage the groove 14. By this construction it will be impossible to remove the guard without breaking the neck of the bottle. The neck of the bottle, which is preferably thickened at the groove 15, extends 25 above the guard 9 to receive an ordinary cork or stopper 16 for enabling the bottle to be sealed in the usual manner.

What is claimed is:

1. A non-refillable receptacle provided with a neck having the lower portion of 35 its opening or passage tapered downwardly, a correspondingly downwardly tapered valve casing arranged within the lower portion of the neck of the bottle, a tapered packing

sleeve surrounding the valve casing and interposed between the same and the tapered 40 interior of the neck of the casing, a valve operating within the valve casing, a packing ring fitted against and extending across the upper edges of the valve casing and the packing sleeve, and an upper guard secured 45 within the neck of the receptacle and seated upon the packing ring and retaining the same in contact with the valve casing and the said sleeve.

2. A non-refillable receptacle provided 50 with a neck having the lower portion of its opening or passage tapered downwardly, a downwardly tapered valve casing arranged within the lower portion of the neck and forming a valve chamber, said valve casing 55 being provided in its upper edge with opposite recesses, a valve operating within the valve chamber, a tapered packing sleeve surrounding the valve casing and interposed between the same and the neck of the bottle, 60 a valve retaining bar extending across the valve chamber and having its ends seated in the said recesses, a packing ring arranged upon and extending across the upper edges of the valve casing and the packing sleeve 65 and confining the valve retaining bar in the said recesses, and a guard within the neck of the receptacle and seated upon the said packing ring.

In testimony that I claim the foregoing as 70 my own, I have hereto affixed my signature in the presence of two witnesses.

LEONARD ROSE.
